UNITED STATES PATENT OFFICE.

MAX FUSS, OF BERLIN, GERMANY.

AUTOMATIC PRESSURE-REGULATOR FOR ELECTRIC MACHINES.

1,215,360.

Specification of Letters Patent. Patented Feb. 13, 1917.

Application filed March 21, 1911. Serial No. 616,013.

To all whom it may concern:

Be it known that I, MAX FUSS, a subject of the German Emperor, and resident of Steinmetzstrasse 30, Berlin, Germany, have invented certain new and useful Improvements in Automatic Pressure-Regulators for Electric Machines, of which the following is a specification.

This invention relates to automatic tension regulators for separately excited electrical generators, the exciting dynamo being provided with a variable shunt resistance in its field.

The invention has for its object to provide an automatic tension regulator comprising a fixed and a movable contact and operating by periodically placing in circuit and short-circuiting a resistance in the field of the exciting dynamo, and wherein the movable regulating medium is a contact lever influenced by the exciter and generator tensions, and which, under their influence, is brought in and out of contact with the fixed contact.

According to the invention the two powers created by the exciter and generator tensions act independently of each other upon a floating contact lever which is arranged so that it can follow each of these powers or both together independently of each other, and not only move against the fixed contact but also be subject to alterations of position according to variations of these powers.

In order that the invention may be readily understood, reference is had to the accompanying drawings showing two mechanical expressions of the inventive idea differing but slightly from each other. The drawings are intended to assist the description but not to define the limits of the invention.

Figure 1 is a diagrammatic illustration of the connections for a tension regulator without current compensation; and

Fig. 2 is a similar view of a pressure regulator with a compensating coil.

In the connection diagram according to Fig. 1, 1 is a rotary current generator with the exciting winding 2, which is fed from the exciting dynamo 3. 4 is the field winding of the exciting dynamo 3 with its field resistance 5. The regulator consists of the exciting solenoid 6 which influences the

iron core 9, and the pressure solenoid 7 with the iron core 10. The iron cores 9 and 10 engage with a floating contact lever 11, beneath which the fixed contact 12 is arranged. The spring 13 engaging with the iron core 9 is opposed to the attraction of the exciting coil 6, while the damper 14 will prevent vibrations of the iron core 10 in the pressure coil 7. The manner of working is as follows:—

Suppose the contact on the lever 11 and the contact 12 touch each other, the resistance 5 is short-circuited and the tension increases; then the solenoid 6 pulls the core 9 up. Thus the contact on the lever 11 leaves the contact 12 and the resistance 5 is placed in circuit with the winding 4. Consequently the tension of the exciting-dynamo 3 decreases, the power of the solenoid 6 diminishes, and the contact on the lever 11 comes again into contact with the contact 12. Therefore, the resistance 5 is again short-circuited and the tension should increase, but in this case, where, as presumed above, the generator tension is increased, the solenoid 7 will operate the core to interrupt the contact. The contact on the lever 11 is thereby periodically brought in and out of contact with the contact 12. If the generator is now loaded in such a degree that the tension decreases, then the core 10 falls and the same working is repeated in the opposite direction. The cores 9 and 10, and with them the lever 11, will consequently, due to different loads, take different positions.

In the connection diagram according to Fig. 2 the arrangement is practically the same as in Fig. 1 only besides the pressure solenoid 7 a current solenoid 8 of opposite effect is employed which will influence the iron core. The current solenoid serves to compensate the drop of pressure in the generator or the system by counteracting the pressure solenoid 7.

I claim:

1. In combination, an electrical generator, an exciter therefor having in circuit a variable resistance and an automatic tension regulator comprising electromagnetic means energized by the electrical condition of the exciter circuit and other electromagnetic means energized by the electrical condition in the

- generator circuit, a fixed contact and a floating contact member in circuit shunting the resistance in the exciting dynamo circuit, and connections between said member and said two named means whereby said exciter and generator circuits act independently of each other upon the floating member to make and break contact with the fixed contact for different floating positions of said member.
5. In combination, a source of current to be regulated, and a separate source of current associated therewith, a pair of contacts one of which is a floating member, electromagnetic means energized by the first-named source of current and other electromagnetic means energized by the other source of current, and connections between said means and said member whereby said means are adapted to support said member in different floating positions while variations of current in said means enable said member to make and break contact with the fixed contact for different floating positions of said member.
10. In a regulator for dynamo electric machines, a stationary contact, a movable arm co-operating therewith to open and close a circuit, a solenoid, a core therefor mechanically connected to said arm, a movable fulcrum for said arm, and another solenoid controlling the movements of said fulcrum.
15. In combination, a dynamo electric machine, a voltage regulator therefor comprising a stationary contact, a movable arm co-operating therewith to determine the excitation of said machine, means, serving as a movable fulcrum point for said arm, responsive to the terminal voltage of said machine, and means responsive to the excitation of said machine for vibrating said arm around said fulcrum, thereby opening and closing said contacts.
20. In combination, a dynamo electric machine, a voltage regulator therefor comprising a stationary contact, a movable arm co-operating therewith intermediate the ends of the arm to determine the excitation of said machine, means, serving as a movable fulcrum point for one end of said arm, responsive to the terminal voltage of said machine, and means, serving as a movable fulcrum point for the other end of said arm, responsive to the excitation of said machine, thereby opening and closing said contacts.
25. An electrical regulator comprising co-operating stationary and movable contact members, and actuating windings for the movable member each of which may actuate the same independently of the other, the energization of one of said windings being governed by the said contact members.
30. In combination, a source of current to be regulated and a separate source of current associated therewith, a pair of contact members, one of which is movable in two different manners, electromagnetic means energized by the first named source of current for moving said contact member in one of said manners and electromagnetic means energized by the other source of current for moving said contact member in the other of said manners.
35. In an automatic governor for electric circuits, the combination with a system of distribution, a generator adapted to supply current to said distributing system and a system for exciting said current generator, of a resistance in said exciting system, a member capable of movement in two different manners, two co-operating contact pieces electrically connected with said resistance, one of said contact pieces being stationary and the other movable and carried by said member, means placed under the control of said exciting system for moving said member in said one manner so as to periodically short-circuit and reinsert said resistance, and means placed under the control of said distributing system for moving said member in said other manner so as to vary the duration of the closing of contact in proportion to the duration of the opening.
40. An electrical regulator comprising co-operating contacts, a movable member actuating one of said contacts, means comprising a winding for actuating said member, means providing a fulcrum for said member, and another winding for actuating said fulcrum providing means.
45. An electrical regulator comprising a stationary contact, a movable contact, a movable member actuating said movable contact, means comprising a winding for actuating said member, means providing a fulcrum for said member, and another winding for actuating said fulcrum providing means.
50. In combination, a source of current to be regulated, and a separate source of current associated therewith, a pair of contacts one of which is a floating member, electromagnetic means energized by the first-named source of current, and other electromagnetic means energized by the other source of current, and connections between said means and said member whereby said means are adapted to support said member in different floating positions while variations of current in said means enable said member to make and break contact with the fixed contact for different floating positions of said member.
55. The combination with a system of distribution, a generator adapted to supply current to said distributing system, and a system for exciting said generator, of a regulator for said generator comprising a resistance in said exciting system, a member capable of movement in two different manners, co-operating contact pieces electrically connected to said resistance, one of said contact pieces being actuated by said member, means for moving said member in said one manner so as to periodically short-circuit

and reinsert said resistance, and means responsive to an electrical condition of said distributing system for moving said member in said other manner so as to vary the 5 duration of the closing of the contacts with respect to the duration of the opening thereof.

In testimony whereof I have signed my name to this specification in presence of two subscribing witnesses.

MAX FUSS.
